UNITED STATES PATENT OFFICE.

ARTHUR R. HAVENER, OF WAYLAND, MASSACHUSETTS, ASSIGNOR TO JUDSON L. THOMSON MANUFACTURING CO., OF WALTHAM, MASSACHUSETTS, A CORPORATION OF MASSACHUSETTS.

RIVET-SLOTTING MACHINE.

Application filed November 12, 1923. Serial No. 674,171.

This invention relates to a machine for slotting the shanks of rivets.

The object of the invention is to provide a machine which will perform the work very rapidly as compared with machines which have heretofore been employed for this purpose. This result is attained by feeding a plurality of rivets to a rotary cutter during one rotation of the cutter, the rivets being held firmly in position during the slotting operation and ejecting mechanism being provided which operates a plurality of times to eject a plurality of rivets from the machine during one rotation of the cutter shaft. The preferred embodiment of my invention hereinafter described and claimed, utilizes a plurality of cutter blades fast to a rotary member and a rivet is fed into position and held in position for each of the cutter blades respectively, which are fastened to said cutter member. In view of the speed with which the rivets must be fed to the cutter blades, it is necessary to feed the rivets successively to a carrier by positively actuated mechanism instead of depending upon gravity to perform this function.

In the embodiment of my invention hereinafter disclosed, two cutter blades are employed, and assuming that the cutter shaft rotates at the same speed as in machines of this class heretofore employed, the number of rivets slotted by the machine in a given time will be twice that of the machine employing a single cutter blade and only feeding one rivet to the cutter blade for one rotation of the cutter shaft.

The invention consists in the combination and arrangement of parts set forth in the following specification and particularly pointed out in the claims.

Referring to the drawings:—

Figure 1 is a front elevation of my improved rivet slotting machine.

Fig. 2 is a side elevation of the same, as viewed from the right of Figure 1.

Fig. 3 is a side elevation as viewed from the left of Figure 1.

Fig. 4 is a detail front elevation of the mechanism for actuating the rivet driver and holder.

Fig. 5 is a detail front elevation of the mechanism which actuates the rivet carrier.

Fig. 6 is a front elevation of the rivet ejecting mechanism.

Fig. 7 is a front elevation, broken away, and illustrating the cutter blades and the rotary member to which they are fastened.

Fig. 8 is a sectional elevation taken on line 8—8, Fig. 7.

Fig. 9 is a detail sectional elevation taken on line 9—9, Fig. 1.

Fig. 10 is a detail elevation viewed in the direction of the arrow *a*, Figure 1, and illustrating the mechanism for feeding the rivets from the raceway to the carrier.

Fig. 11 is a detail elevation similar to Fig. 10, showing the parts in different relative positions.

Fig. 12 is a side elevation of a slotted rivet.

Fig. 13 is an enlarged front elevation partly in section, illustrating the driver in its lowermost position and a rivet ready to be fed into the rivet carrier and another rivet held in position for slotting, with a portion of the cutter shown in operative position.

Fig. 14 is an elevation viewed in the direction of the arrow *d*, Fig. 13, the work support and ejector plate being shown in section.

Fig. 15 is a plan view viewed in the direction of the arrow *c*, Fig. 13, illustrating the ejector plate and a portion of the work support. Fig. 16 is a detail cross section taken on line 16—16, Figure 15.

In practical operation the machine is positioned with the median longitudinal line of the driver at an angle of about 60° to a horizontal plane, as illustrated in Fig. 13.

Like numerals refer to like parts throughout the several views of the drawings.

In the drawings, 15 is the frame of the machine, 16 is the cutter shaft which is rotated by a pulley, or other suitable means, not shown in the drawings. A gear 17 is fastened to the cutter shaft 16 and meshes into another gear 18 fast to a cam shaft 19. The gear 17 having twice the pitch diameter of the gear 18, so that one rotation of the cutter shaft 16 rotates the cam shaft 19 twice. The cutter blades 20 and 21 are clamped between two discs 22 and 23 by a nut 24 and collar 25, see Figs. 7 and 8.

The cutting edges 20' and 21' of the cutter blades 20 and 21 respectively are eccentric to the axial line of the cutter shaft 16, and in the operation of the machine the cutter 5 as a whole, consisting of the discs 22 and 23 and the cutter blades 20 and 21, rotates in the direction of the arrow *b*, Fig. 7.

The rivets 26, to be slotted, are fed from a hopper, in a manner well known to those skilled in this art, down a raceway 27 and are fed from the bottom of the raceway, one by one, to an auxiliary raceway 28 by a slide 29, there being a slot 30 in said slide to receive the rivet when it is being transferred 15 from the raceway 27 to the raceway 28.

This construction is old in the art and is fully described in United States Letters Patent Nos. 879,895 and 879,896 to J. E. Perault, patented February 25, 1908, "Machine 20 for setting rivets", to which reference may be had in this connection.

The rivets 26 slide one at a time down the raceway 28 until the lowermost rivet 26' engages a driver and holder 31, as illustrated in Figs. 13 and 14.

A reciprocatory motion is imparted to the slide 29 by a lever 32 pivoted at 33 to the frame of the machine and having a rocking motion imparted thereto by a spring arm 34, 30 the free end of which projects through a hole 35 in the arm 36 of said lever 32. The spring arm 34 is fastened to a split block 37 which is clamped by a screw 38 to a rod 39 see Fig. 2. A reciprocatory motion is imparted to the rod 39 by a cam 40, Figs. 2 and 4 fast to the cam shaft 19 and by a spring 41, one end of which is fastened to a pin 42, and the other end to an ear 43 on the hub 44 of an arm 45. The slide 29 slides in 40 ways provided upon the frame of the machine and has rigidly fastened to the front end thereof an arm 46, to the lower end of which is fastened a feed finger 47, see Figs. 10 and 11 13 and 14. The feed finger 47 is positioned to pass above the shank of the rivet 26' on the raceway 28 when the slide 29 is moved toward the right, from the position illustrated in Fig. 10 to the position illustrated in Fig. 11, and by this movement 50 the finger 47 will positively force the rivet 26' on the raceway 28 against the driver 31 and in so doing the feed finger 47, which is of thin flat material and resilient, will be brought into tension, so that when the driver 31 is moved upwardly, until the lower end thereof is above the head of the rivet 26', the rivet 26' will be immediately forced into a rivet carrier 48, which consists of two side plates 49, each of which is fastened to a flat spring 50, and said flat springs are fastened, by means of a bolt 51 and a nut 52 to a carrier slide 53, see Figs. 3 and 5.

A reciprocatory motion is imparted to the 60 slide 53 by a cam 54 which is engaged by a cam roll 55 journalled upon an arm 56, see

Figs. 2 and 5, the arm 56 being fast to a rock shaft 57 journalled upon a bearing 58 on the frame of the machine. The opposite end of the shaft 57 has another arm 59 fast thereto, to the upper end of which is fastened 70 a pin 60 which projects through a slot 61 in one end of a link 62, the other end of said link being pivotally connected at 63 to an arm 64 fast to a rock shaft 65, Figs. 1, 3 and 5. The rock shaft 65 is journalled to 75 rock in a bearing 66 on the frame of the machine, see Fig. 3, and the front end of said rock shaft has an arm 67 fast thereto and provided at its outer end with a pin 68 which carries a sliding block 69, sliding in 80 a slot 70 which is provided in a block member 70' clamped to the upper end of the carrier slide 53. A spring 71 is connected at one end to the pin 60 and at the other end to the pin 63 and normally holds the 85 pin 60 in engagement with the left hand end of the slot 61, see Fig. 5, while the roll 55 on the arm 56 is held in engagement with the cam 54 by a spring 72. This mechanism provides yielding means between the cam 54 and the carrier 48, in the event of any obstruction to the normal operation of the device occurring.

A reciprocatory motion is imparted to the rivet driver and holder 31, Figs. 1 and 4, 95 by a slide 73 arranged to slide in ways provided in the frame of the machine and driven by a link 74 and arm 75 which is fastened to a rock shaft 76 journalled in 100 bearings 77 and 78 in the frame of the machine.

A rocking motion is imparted to the rock shaft 76 by an arm 79 which is connected by the pin 42 to the rod 39, to which a reciprocatory motion is imparted by the cam 40, 105 are hereinbefore set forth.

The rivet 26', see Fig. 9, is driven by the driver and holder 31 out of the rivet carrier 48 and into a hole 80 in the work support 81. The work support 81 is fast to the frame 110 of the machine and has a ridge 82 extending upwardly therefrom and longitudinally thereof, upon which the head of the rivet 26' rests, and upon which it is firmly held by the rivet driver and holder 31.

When the parts are in the positions illustrated in Fig. 9, the rivet is in readiness to be slotted by one of the cutter blades 20 or 21 and after it has been slotted, the rivet driver and holder moves upwardly and the rivet is ejected from the machine into a tray 83, see Figure 1, by an ejector plate 84, which is bifurcated at 85 at the forward end thereof, so that the rivet 26' may project therethrough.

The ejector plate 84 is fastened to an arm 86, which is fastened to a rock shaft 87 journalled to rock in a bearing 88 in the frame of the machine and having fastened to its rear end the arm 45, to which motion is im- 120 125 130

parted by a cam 88' fast to the cam shaft 19 and engaging a cam roll 89 rotatably mounted upon a pin 90 on the lower end of the arm 45.

The general operation of the mechanism hereinbefore specifically described is as follows:—

Rivets to be slotted are fed from a hopper, not shown in the drawing, but in a manner well known to those skilled in the art, down the raceway 27 and are transferred one by one from the bottom of said raceway by the slide 29 to the auxiliary raceway 28. The lowermost rivet 26' in said auxiliary raceway is transferred to the carrier 48 by the feed finger 47, actuated by the arm 46, and slide 29 in a manner hereinbefore described. Said rivet 26' having been transferred to the carrier 48 is carried downwardly by 10 said carrier toward the work support 81 and is then driven by the driver and holder 31 downwardly out of the carrier 48 and into the hole 80 in the work support 81, with its head resting upon the ridge 82 forming a 15 part of said work support. When in this position, the bifurcated portion 85 of the ejector plate 84 projects beneath the head of the rivet 26' and the rivet is held firmly in position by the rivet driver and holder 31 and by the slide 73, link 74 and arm 75, it being noted that when in this 20 position the link 74 and arm 75, which together form a toggle, are positioned on dead centers.

It is very desirable that the driver and holder 31 when feeding the rivet downwardly out of the rivet carrier 48 should be actuated by a yielding or spring pressure, but that it should be held rigidly in position against the head of the rivet 26' when the slotting operation is taking place and this is accomplished by the mechanism illustrated particularly in Figs. 2 and 4 wherein it will be noted, as hereinbefore specifically set forth, 25 that the spring 41 acts to rock the arms 75 and 79 downwardly and the cam 40 acts to rock said arms upwardly so that the slide 73 and driver 31 through the link 74 are moved downwardly with a yielding pressure 30 by means of the spring 41, but the arm 75 and link 74 when in their downward position, as shown in Fig. 4, constitute a toggle with the pivots on dead centers so that the driver and holder 31 when in that position 35 is positively locked against any upward pressure and the rivet 26' is locked in position while being slotted by the rotary cutter. The driver and holder 31, slide 73, link 74 and the arms 75 and 79 on their upward movement are positively actuated by the cam 40. The object of this construction 40 is to avoid damage to the different parts hereinbefore referred to, that is, to the different parts which actuate the driver 30 and holder 31 so that in case a rivet is not in the

proper position in the rivet carrier 48 when the rivet is being driven down by the driver and holder, the driver and holder will stop in its downward movement and will not injure any of the mechanism which is engaged by it or by the rivet, or any of the mechanism which actuates the driver.

The rivet 26' is now slotted by one of the cutter blades 20 or 21 and after the slotting operation has been performed the rivet 75 driver and holder moves upwardly and the ejector plate 84 is actuated to eject the rivet from the machine and into the tray 83. Another rivet is now fed and held in position to be slotted, as hereinbefore described, 80 and will be slotted by the other of the two cutter blades 20 or 21 and ejected from the machine, after being slotted by the ejector plate 84.

I claim:

1. A rivet slotting machine having, in combination, a rotary cutter, mechanism to feed a plurality of rivets to said cutter during a single rotation thereof and means to hold said rivets in position while the cutter 90 during a single rotation successively completes the slotting of the shanks thereof.

2. A rivet slotting machine having, in combination, a rotary cutter, mechanism to positively feed a plurality of rivets to said cutter during a single rotation thereof and means to hold said rivets in position while the cutter 95 during a single rotation successively completes the slotting of the shanks thereof.

3. A rivet slotting machine having, in combination, a rotary cutter, mechanism to feed a plurality of rivets successively to said cutter during a single rotation thereof and means to hold said rivets in position while the cutter 105 during a single rotation successively completes the slotting of the shanks thereof.

4. A rivet slotting machine having, in combination, a rotary member, a plurality 110 of cutter blades fast thereto, mechanism to feed a rivet to each of said cutter blades respectively during a single rotation of said rotary member, and means to hold said rivets in position while said cutter blades, during a single rotation of said rotary member, successively complete the slotting of the shanks thereof.

5. A rivet slotting machine having, in combination, a rotary cutter shaft, a cutter fast thereto, a cam shaft and cams, mechanism to rotate said cam shaft and cams a plurality of times to a single rotation of said cutter shaft, mechanism actuated by said cams to feed a plurality of rivets to said cutter during a single rotation thereof and means actuated by one of said cams to successively hold said rivet in position while said cutter is slotting the shanks thereof.

6. A rivet slotting machine having, in 130

combination, a rotary cutter shaft, a cutter member fast thereto, a plurality of cutter blades fast to said cutter member, a cam shaft and cams, mechanism to rotate said cam shaft and cams a plurality of times to a single rotation of said cutter shaft, mechanism actuated by said cams to feed a rivet to each of said cutter blades respectively during a single rotation of said cutter shaft and means actuated by one of said cams to hold said rivets in position successively while said cutter blades are slotting the shanks thereof.

7. A rivet slotting machine having, in combination, a rotary cutter, a rivet carrier, a raceway, mechanism to positively feed rivets from said raceway on to said carrier, a work support, a driver, and mechanism to move said driver to feed a plurality of rivets successively from said carrier on to said work support during a single rotation of said cutter and to successively hold said rivets in position on said work support while said cutter, during a single rotation thereof, is successively slotting the shanks of a plurality of said rivets.

8. A rivet slotting machine having, in combination, a rotary cutter, a rivet carrier, a raceway, mechanism to feed rivets from said raceway on to said carrier, a work support, a driver, mechanism to move said driver to successively feed a plurality of rivets from said carrier on to said work support and hold said rivets in position while said cutter, during a single rotation thereof, is slotting the shanks of said rivets, an ejecting lever positioned beneath the head of each rivet during the slotting operation and mechanism to move said ejecting lever a plurality of times during one rotation of said

cutter to eject a plurality of rivets from said machine after the slotting operation has been performed.

9. A rivet slotting machine having, in combination, a rotary cutter, a rivet carrier, a raceway, mechanism to feed a plurality of rivets successively from said raceway on to said carrier during a single rotation of said cutter, a work support, a driver, a slide to which said driver is fastened, mechanism embodying a toggle joint to impart a plurality of reciprocatory motions to said slide and driver during a single rotation of said cutter and feed said rivets successively from said carrier on to said work support and rigidly hold them successively in position while said cutter, during a single rotation thereof, is successively slotting the shanks of said rivets, and means to eject successively a plurality of rivets during one rotation of said cutter.

10. A rivet slotting machine having, in combination, a rotary cutter, a rivet carrier, a raceway, mechanism to positively feed a rivet from said raceway onto said carrier, a work support, a driver and mechanism to move said driver to yieldingly feed a rivet from said carrier onto said work support and positively hold said rivet in position thereon while said cutter is slotting the shank thereof, said rivet-feeding mechanism and driver-actuating mechanism being operable to successively feed and position two rivets to be slotted by said cutter during one rotation thereof.

In testimony whereof I have hereunto set my hand.

ARTHUR R. HAVENER.
